UNITED STATES PATENT OFFICE

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

No. 841,254.

Specification of Letters Patent.

Patented Jan. 15, 1907.

Application filed July 10, 1905. Serial No. 268,916.

To all whom it may concern:

Be it known that I, OSCAR JUNGGREN, a citizen of the United States, residing at Schenectady, county of Schenectady, State of New York, have invented certain new and useful Improvements in Elastic-Fluid Turbines, of which the following is a specification.

The present invention has for its object to improve the efficiency of elastic-fluid turbines, and especially by overcoming or largely reducing the losses caused by the action of the motive fluid after it is exhausted from one wheel and before it enters the nozzles of the next stage of lower pressure.

In carrying out the invention a suitable casing is provided across which extend dia-phragms or walls that divide it into compartments or stages. The casing is provided with internal shoulders that receive and support the dia-phragms. Carried by these shoulders and also by the head of the machine are suitable nozzles or devices for discharging motive fluid against the wheel-buckets. Mounted on the shaft and revolving in the stages or compartments are wheels, each carrying one or more rows of peripheral buckets.

I have discovered that between the exhaust side of the wheel in any given stage and the adjacent nozzles or other devices receiving motive fluid therefrom there should be a substantial space in order to prevent a choking or retarding effect on the motive fluid which follows when the parts are close together. I have also discovered that where the wheel is located in a compartment with a relatively large free space around it the rotation of the wheel produces objectionable eddy-currents, resulting in losses. This is due largely to the fact that the idle rotating buckets exert a fan-like action. The skin-friction between the body of fluid in the chamber also results in a loss. Again, these eddy-currents tend to disturb the passage of motive fluid through the adjacent nozzles of lower pressure.

I overcome the objections above set forth by providing the wheel-compartment of each stage except the last with a receiving-chamber into which the steam or other motive fluid is freely discharged, the receiving-chamber in turn supplying steam to the various nozzles. These chambers may extend over only a limited arc, if desired; but I prefer to have them extend entirely around the wheel.

The entrance to the chamber may with advantage be in the form of a circumferential throat or slot which is of substantially the same width as the fluid column discharged by the wheel. At a point beyond the throat the annular chamber enlarges rapidly and is of sufficient size to freely receive all of the steam, equalize the pressures of the different streams when the preceding bucket-wheel is fed by two or more nozzles or sets of nozzles, and equalize the pressure of and feed the various nozzles of lower pressure connected therewith. Owing to the construction of the receiving-chambers, the steam contained therein is cut off from the effects of the rotating wheel; and hence the rotation losses are reduced.

The receiving-chambers may be formed between the internal shoulder on the casing and one or more detachable pieces or they may be cored out of the casting itself. The particular construction can be widely varied. The wall of the receiving-chamber adjacent to the bucket-wheel in addition to functioning as such assists in cutting down rotation losses due to the fan-like action of the idle buckets by presenting a smooth flat surface to the edges thereof. This last statement applies only when the active buckets occupy less than the entire circumference. These walls are located in close proximity to the ring-like supports on the wheels to which the buckets are secured. Hence they coöperate with said supports to prevent the steam from passing freely into that portion of the wheel-compartment immediately surrounding the shaft. In other words, they prevent heavy cross-currents of steam from flowing at right angles to the shaft between the wheels and the dia-phragms.

Another and important feature of my invention resides in the fact that by the use of the internal shoulders and receiving-chambers the nozzles in the low-pressure stages can be arranged to deliver fluid to the entire bucket circumference, and this without unduly weakening the parts or making them complicated, which has been the great objection in the past.

The arrangement described lends itself particularly well to those machines having automatic valves between stages which open and close in response to variations in stage-pressure and serve to hold the stage-pres-

sures constant, or substantially so. The valves may with advantage be mounted in casings that are bolted to the wheel-casing, so that they may be readily assembled and removed. The arrangement of the parts is such that the ports or passages controlled by the valves are connected on the inlet side to the receiving-chambers and on the outlet side to an auxiliary nozzle or nozzles, the latter only receiving steam when the valves are open. As many of these valves are provided as are necessary to properly handle the motive fluid. They may be used between two stages only or they may be used between two, three, four, or more, depending upon the character of the turbine and the total number of stages. The valves are so constructed that they expose a greater area when open than when seated, the object being to prevent the valves from chattering. Each valve is provided with an indicator, which shows at all times its position and enables the attendant to detect at once any irregularity or failure in operation. The valves in each stage are preferably so arranged that they open successively, since by so doing a more nearly even pressure will be maintained in the several stages.

The annular walls forming the receiving-chambers are separated from the sides of the rings or segments thereof forming the bases of the buckets by clearances which are substantially the same as the clearances between the moving and stationary buckets. By preference the clearances at these points are slightly less than the bucket clearances, so that any rubbing which may take place, due to distortion or accident, will occur on parts of substantial size and rugged construction.

In the accompanying drawings, which illustrate one embodiment of my invention, Figure 1 is a quarter-section of a vertical-shaft turbine of the Curtis type. Fig. 2 is a sectional view taken on line 2-2 of Fig. 1. Fig. 3 is a detailed sectional view showing a modified arrangement of one of the annular chambers which receives the motive fluid exhausted from a bucket-wheel. Fig. 4 is a detail sectional view, on an enlarged scale, of a pressure-actuated stage-valve. Fig. 5 is a sectional view of a low-pressure stage, showing a complete range of nozzles; and Fig. 6 is a detail sectional view showing the passages leading from the stage-valves.

1 represents the casing of the turbine, which is supported by a base 2, that contains an exhaust-chamber 3, the latter being connected to atmosphere or a condenser, as desired. The turbine illustrated is intended for atmospheric exhaust.

4 represents the top or head of the machine, which is bolted to the casing.

The interior of the casing is divided into stages by diaphragms 5. These diaphragms

are made something smaller in diameter than the wheels in order to reduce the strains thereon. They are supported at the periphery by shoulders 6, that are cast integral with the casing. The casing is made up of a number of sections which are securely bolted together, the plane of division between the sections being axial. By means of this arrangement one of the sections can be removed without interfering with the others. Located in each stage or compartment is a wheel 7, provided with rows of buckets 8. The wheels are mounted on a vertical shaft 9, the latter being supported by a step-bearing 10, the upper end of which is shown. The shaft extends upward through an opening in the head and is provided with carbon packing-rings 11 for preventing the escape of steam or other elastic fluid. Between the rows of wheel-buckets are rows of intermediate buckets 12. These buckets are mounted upon a support which is L-shaped in cross-section. The support is located in an internal groove in the wheel-casing and is retained in place by bolts which are accessible from the inside of the wheel-casing.

Steam or other elastic fluid is delivered to the bucket-wheels by sectionalized nozzles, which may be expanding or non-expanding in character. The admission-nozzles 13 are bolted to the head 4 and the stage-nozzles are bolted to the internal shoulders 6. The motive fluid is admitted to the turbine by means of separately-actuated valves 14. In the present instance these valves are located in the chest 15 and are opened and closed in response to pressure changes by the pistons 16 under the control of a governor. For the purpose of illustration the position of the admission-valves has been shown as displaced by an angle of ninety degrees, so that one section will show both the admission and the stage valves. In the present machine two valve-chests 15 are provided (only one of which is shown) and located at diametrically opposite points. This means that when the machine is in operation two columns of fluid are simultaneously passing through the buckets of the first wheel. Situated directly below the buckets of the first wheel and receiving steam therefrom is an annular chamber 17. This annular chamber is formed in part by the shoulder 6 and the detachable segmental walls 18. These walls may extend over an arc corresponding to a casing-segment or two or more sections may be provided therefor. The latter are bolted to the shoulder 6 and to the inner wall of the casing. These segmental walls are provided with a circumferential slot or opening 19, which forms a throat for the annular chamber 17.

Referring now to Fig. 2, it will be seen that the throat 19 covers the arc corresponding to the casing-section 20. In other words, it covers substantially the same arc as the ad-

mission-nozzles. The arrangement of the parts is similar on the opposite side of the machine, and the throat is directly under the valve-chest 15. It is to be noted that the 5 segmental walls 21, that form a part of the annular chamber between the casing-sections 20 and 22 of the wheel-casing, are not provided with a throat. This is due to the fact that the first stage-wheel is idle between 10 these two points. In order to prevent or largely reduce the fan-like action of the idle buckets while moving from one column of steam to the other, the segmental walls 21 are provided with smooth flat surfaces 23, 15 that are separated from the wheel by small clearances, preferably about the same as those between the wheel and intermediate buckets. These walls serve to prevent the buckets from rubbing if for any reason the 20 wheel is distorted or the step-bearing is improperly set. In other words, the walls of the annular chamber not only act as such, but also to reduce the rotation losses and prevent accidents to the buckets.

25 The annular chamber 17 is arranged to supply the main second-stage nozzles located directly under it and in line with the valve-chests 15. The general arrangement of these parts is the same as that shown in the lower 30 right-hand corner of Fig. 1. The arc covered by the nozzles increases step by step for each stage, and in the last stage the nozzle extends entirely around the wheel, so that all of the buckets are active. In addition to the 35 main nozzles in the second stage are auxiliary nozzles 24, which are controlled by the pressure-actuated stage-valves. 25 represents one of these stage-valves, which is provided at its upper end with a removable seat 26.

40 The upper end of the valve is provided with a groove having tapered walls, which when the valve is closed engage with the seat. The object of this arrangement is to prevent chattering to the valve by providing a materially 45 greater area for the valve when open than when closed. The space above the valve communicates with the annular chamber 17 and the space below with the passage 26^a, that communicates with a small segmental 50 chamber 27, formed in the internal shoulder 6. The arc covered by this chamber is dependent upon the number of nozzles to be controlled. This arrangement is best shown in Figs. 2 and 6, where the stage-valve 28 55 controls the admission of fluid to the three groups of openings 29, which supply the stage-nozzles directly underneath. Situated directly underneath the openings 29 is a segmental passage or chamber 29^a, that equalizes the pressure of the several streams issuing 60 from the openings and supplies steam to the bowls of the auxiliary stage-nozzles 24. The valve 30, contained in the same casing, controls the passage of fluid to the three 65 groups of openings 31, Figs. 2 and 6. These

valves are set by means of the springs 32, Fig. 1, to operate successively. The valves 33, 34, 35, and 36 control passages leading from the second to the third stage and are arranged to operate successively in order to maintain 70 the stage-pressures as uniform as possible. The construction of each one of these valves is the same as illustrated in Figs. 1 and 4. The object in providing a greater number of stage-valves between the second and third 75 stages than between the first and second is to accommodate the increased volume of fluid due to the reduced pressure.

In order to show the position of the stage-valves when the machine is in operation, 80 each valve is provided with a spindle 37, that extends through a suitable packing carried by the casing. The outer end of this stem is provided with suitable indicators, and situated adjacent thereto is a pointer 38. By 85 comparing the position of the stem 37 with the pointer the station attendant is able to tell at a glance whether or not the valves are open or closed or working properly.

In Fig. 3 is shown a slight modification, 90 wherein the chamber 17 is formed by coring out the internal shoulder 6 on the wheel-casing. This arrangement has the advantage of decreasing the amount of machine-work; but it is a somewhat more difficult casting to 95 make. The upper wall of the chamber is located in close proximity to the revolving wheel and performs the same function as the detachable segmental walls 21, Fig. 2. In order to further decrease the rotation losses 100 of the idle wheel-buckets, a blank wall 39 is provided, forming a continuation of the nozzles in the first stage. Connecting the adjacent ends of the segmental rows of intermediates is a blank wall 40, which also assists in 105 decreasing the fan-like action of the idle buckets. These blank walls are supported in the same manner as the intermediate buckets themselves.

When the machine is intended for condensing service, additional stages having the same or different construction are provided. The number of high-pressure stages may be changed to suit the requirements without departing from my invention.

In Fig. 5 is shown in section a stage wherein all of the wheel-buckets are active and the stage-nozzle extends entirely around the wheel. The annular chamber for receiving the exhaust from the preceding wheel is provided with a throat, which extends entirely around. The chamber may be formed in the internal shoulder or formed partly by the shoulder and partly by detachable segmental walls. In either case the shoulder should be provided with ribs of substantial size to sustain the pressure on the diaphragm and also with passages or chambers which serve to properly supply steam to all of the nozzle-passages.

In Fig. 6 is shown a sectional view, on an enlarged scale, of the wheel-casing 1 and internal shoulder 6. The passage 26^a on the right is controlled by the stage-valve 28 and the one on the left by the stage-valve 30. These passages supply steam to the openings 29 and 31, and the latter in turn discharge into the segmental chambers or passages 29^a, Fig. 1, communicating with the auxiliary stage-nozzles 24.

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. In an elastic-fluid turbine, the combination of a wheel having rows of buckets thereon, a casing having a compartment to receive the wheel, intermediate buckets arranged in rows between the wheel-buckets, and a chamber for receiving the motive fluid exhausting from the wheel, the wall of which is separated from the wheel by a clearance which does not exceed that of the buckets.

2. An elastic-fluid turbine comprising a plurality of separate stages each including a wheel and a compartment therefor, and nozzles or devices which discharge separate columns of motive fluid to the wheel, in combination with a chamber which receives the columns of fluid exhausting from the wheel and permits them to equalize, throats for the chamber which conform in shape to the columns, and nozzles or devices which receive the fluid from the chamber and discharge it to a point of lower pressure.

3. In an elastic-fluid turbine, the combination of a casing, a diaphragm for dividing it into compartments, a shoulder on the casing which supports the diaphragm, wheels located in the compartments, devices discharging fluid thereto, and an annular chamber which receives the exhaust from a wheel and is located within the casing and surrounds the diaphragm.

4. In an elastic-fluid turbine, the combination of a casing, diaphragms for dividing it into compartments, shoulders on the casing which support the diaphragms, bucket-wheels located in the compartments, devices discharging motive fluid against the buckets, and chambers located within the casing which receive the exhaust from the wheels and supply it to the discharging devices of lower pressure, the said chambers having walls formed by the shoulders.

5. In an elastic-fluid turbine, the combination of a casing, a diaphragm for dividing it into compartments, a shoulder on the casing which supports the diaphragm, wheels lo-

cated in the compartments, devices discharging fluid thereto, an annular chamber which receives the exhaust from a wheel, and segmental detachable pieces which form a wall for the chamber.

6. In an elastic-fluid turbine, the combination of a casing, a diaphragm for dividing it into compartments, a shoulder on the casing which supports the diaphragm, wheels located in the compartments, an annular chamber which receives the exhaust from a wheel, a wall therefor which is formed by the shoulder, admission nozzles or devices, and fluid-discharging devices which are carried by the shoulder.

7. In an elastic-fluid turbine, the combination of a casing divided into two or more stages, each containing a wheel-compartment, bucket-wheels therein, an internal shoulder on the casing, an annular nozzle 8, comprising separate passages which discharge fluid against the adjacent wheel, and an annular chamber that receives the fluid column or columns from the preceding stage and delivers it to the passages of the annular nozzle.

8. In an elastic-fluid turbine, the combination of a casing having an internal shoulder, a diaphragm of less diameter than the bucket-wheels that divides the casing into compartments and is supported by the shoulder, bucket-wheels mounted in the compartments, an annular nozzle supported by the shoulder, and an annular chamber located in line with the shoulder which receives fluid exhausting from one wheel and delivers it to the annular nozzle.

9. In an elastic-fluid turbine, the combination of a casing, an internal shoulder thereon, a nozzle carried by the shoulder which is provided with a plurality of passages, and an annular chamber formed in the shoulder which supplies the nozzle-passages.

10. In an elastic-fluid turbine, the combination of two or more stages, a bucket-wheel in each stage-compartment, an annular chamber which receives the exhaust from a wheel and keeps it out of the influence thereof, nozzles which discharge fluid to a wheel of lower pressure, and valves which control the passage of fluid from the annular chamber to the nozzles, the said valves being sensitive to variations in stage-pressure and arranged to present a greater area when open than when closed to prevent chattering.

11. In an elastic-fluid turbine, the combination of two or more stages, a bucket-wheel in each stage-compartment, an annular chamber which receives the exhaust from a wheel and keeps it out of the influence thereof, nozzles which discharge fluid to a wheel of lower pressure, valves which control the passage of fluid from the annular chamber to the nozzles, the said valves being sensitive to variations in stage-pressure and arranged to

present a greater area when open than when closed to prevent chattering, and indicators which show the positions of the valves.

12. In an elastic-fluid turbine, the combination of a casing containing a compartment, a wheel located therein, rows of buckets mounted on the wheel, intermediate buckets situated between the rows of wheel-buckets, a support for the intermediate buckets which is L-shaped in cross-section, and bolts that pass through the support into the casing for securing the former in place.

13. In an elastic-fluid turbine, the combination of a segmental casing containing a wheel-compartment, a bucket-wheel, and an annular chamber which receives the fluid exhausting from the wheel, the said chamber being provided with segmental walls the joints of which register with those of the casing so that they may be handled as a unit.

14. In an elastic-fluid turbine, the combination of a casing containing a compartment, a bucket-wheel mounted therein, segmental walls that form a receiving-chamber, a throat of relatively restricted area through which the exhaust from the wheel passes into the chamber, and a valve for controlling the passage of fluid from the chamber.

15. In an elastic-fluid turbine, the combination of a casing containing a compartment, bucket-wheels mounted therein, an annular chamber communicating with the wheel-compartment, and segmental throats for the chamber through which the exhaust from the wheel passes, the said throats being angularly displaced.

16. In an elastic-fluid turbine, the combination of a casing containing compartments, bucket-wheels mounted therein, an annular chamber, a throat or opening through which the exhaust from a wheel enters the chamber, main and auxiliary stage-nozzles which are supplied with motive fluid from the chamber, and a stage-valve which controls the passage of fluid to an auxiliary stage-nozzle.

17. In an elastic-fluid turbine, the combination of a casing containing compartments, bucket-wheels mounted therein, an annular chamber, a throat or opening through which the exhaust from a wheel enters the chamber, main and auxiliary stage-nozzles which are supplied with motive fluid from the chamber, and a stage-valve which controls the passage of fluid to an auxiliary stage-nozzle.

18. In an elastic-fluid turbine, the combination of separate stage-compartments, a bucket-wheel in each compartment, a shoulder, an annular chamber in the shoulder which receives the exhaust from a preceding wheel and prevents it from affecting the moving parts, ribs extending across the chamber to support one portion of the shoulder, and an annular nozzle which receives motive fluid from the chamber and discharges it under predetermined velocity to the adjacent wheel.

In witness whereof I have hereunto set my hand this 7th day of July, 1905.

OSCAR JUNGGREN.
